LIP ROUGE CONTAINER

Merton T. Strommen, Arcadia, Calif., assignor to Trulip,
Inc., Arcadia, Calif., a corporation of California
Application February 24, 1956, Serial No. 40,310

Term of patent 14 years

(Cl. D86—10)

FIG. 1.

FIG. 2.

FIG. 3.

FIG. 4.

Fig. 1 is a front elevational view of a lip rouge container showing my new design;

Fig. 2 is a rear elevation view thereof;

Fig. 3 is a plan view thereof; and

Fig. 4 is an end elevational view thereof.

I claim:

The ornamental design for a lip rouge container, substantially as shown.
